[57] **CLAIM**

The ornamental design for an ivy leaf wire ring, as shown and described.

DESCRIPTION

FIG. 1 is a perspective view of the ivy leaf wire ring showing my new design;

FIG. 2 is a bottom plan view of the ivy leaf wire ring;

FIG. 3 is a front side elevational view of the ivy leaf wire ring;

FIG. 4 is a rear side elevational view of the ivy leaf wire ring;

FIG. 5 is a left side elevational view of the ivy leaf wire ring;

FIG. 6 is a right side elevational view of the ivy leaf wire ring; and,

FIG. 7 is a top plan view of the ivy leaf wire ring.

The broken lines showing of the shade is for illustrative

purposes only and forms no part of the claimed design.
